(57) **CLAIM**

The ornamental design for an electronic device, as shown and described.

DESCRIPTION

FIG. 1 is a perspective view of an electronic device showing our new design.

FIG. 2 is a top view thereof.

FIG. 3 is a front view thereof.

FIG. 4 is a rear view thereof.

FIG. 5 is a left side view thereof.

FIG. 6 is a right side view thereof; and,

FIG. 7 is a bottom view thereof.

The broken line showings in the figures are included for the purpose of illustrating portions of the electronic device and form no part of the claimed design. The stipple shading in the figures represent a contrast of appearance. The line shading in the figures are included for the purpose of illustrating contour.
